UNITED STATES PATENT OFFICE

NEWTON D. HOLBROOK, OF THOMASTON, CONNECTICUT

OPERATING MECHANISM FOR TIMEPIECES

Application filed February 7, 1928. Serial No. 252,487.

This invention relates to mechanism which is designed for driving the time train of watch and clock movements in which the source of power is electrical, and while it is serviceable for electric clocks generally it is particularly adapted for time pieces used on automobiles. Automobile time pieces are subject to intensive vibration and unless the power is maintained uniform the regularity 10 of beat and accuracy of time-keeping is seriously affected, there is liability of over-banking with the result that they fail to run correctly if they do not stop. Such a mechanism is illustrated and described in my Patent No. 15 1,662,920, granted March 20, 1928.

The object of this invention is to provide a simple and reliable mechanism which is actuated for tensioning the main driving spring by periodical electric impulses, the 20 intervals of which are controlled by the running of the time train.

This end is attained in the mechanism herein chosen for illustration by providing an electromagnet with two armatures, a main 25 driving armature and a supplemental circuit controlling armature carried by the main armature, both of which are subject to the influence of the magnet. The main armature under the pull of the magnet tensions the time 30 train driving spring, which spring as the time train runs causes the main armature to recede from the magnet until the supplemental armature closes the electrical circuit and the main armature is again drawn by the 35 magnet and the spring retensioned. The supplemental armature carries a contact which closes the circuit through the magnet when the main armature has receded to the desired degree, and is caused to open the circuit when 40 the main armature is attracted substantially its full distance, the supplemental armature being carried by the main armature and subjected to the pull of the magnet with a lost motion connection. A spring is arranged to 45 engage and delay or retard the movement of the supplemental armature so that the circuit contacts are not instantly disengaged when the main armature is attracted but are held closed for a short interval by the pull of the 50 magnet on the supplemental armature. The

driving mechanism is connected with the time train driving arbor by positive means but which is capable of slight expansion so as to keep the connection close at the instant that the main spring is tensioned, and thus contribute in maintaining the even driving pressure on the time train. 55

In the accompanying drawings Fig. 1 is a view looking toward the back of a driving mechanism which embodies the invention, the parts being in the position occupied when the electric circuit is closed. Fig. 2 is a similar view with the circuit open. Fig. 3 is a view looking at the front of this mechanism. Fig. 4 is a view looking at one side of the driving mechanism. Fig. 5 is a view looking at one end of the driving mechanism. Fig. 6 shows an edge view of the means whereby the driving mechanism is connected to the driving arbor of the time train. Fig. 7 is a plan view 70 of a portion of the connecting means. 60

In the form of mechanism illustrated herein the magnet coils 1 are wound upon a core 2 which extends completely through the coils and that at one end has an extension 3, thus 75 providing poles at both ends of the magnet. The magnet is fixed to the back of a plate 4 and pivotally mounted on a post 5 that projects from the back of the plate is an L-shaped driving lever 6. This driving-lever 80 is made of magnetic metal and comprises a main or primary-armature arm 7 extending across the core at one end in position to be attracted thereby, and an arm 8 that extends along the side of the magnet, the pivotal point 85 of the lever being at the apex of the angle. On the back side of the plate the swinging end of the arm 8 is bent outward and has a slot 9, and extending from the arm 8 through an opening 10 in the plate is a lug 11. Pivoted to this lug is a driving pawl 12 which is held in engagement with the ratchet wheel 13 on the front of the plate by the main driving spring 14. The driving spring is so arranged that it holds the pawl in engagement with and tends to drive the ratchet wheel forward, and also tends to pull the arm 8 in such a direction as to cause the arm 7 of the armature to recede from the core of the magnet as the spring through the pawl 100 90 95

drives the ratchet wheel forward. When the arm 7 is drawn toward the core by the pull of the magnet the main driving spring 14 is retensioned and the driving pawl retracted over the ratchet teeth. A drag pawl 15 is held by a spring 150 in engagement with the ratchet wheel to prevent the backward movement of the ratchet wheel when the driving pawl 12 is retracted.

10 The secondary or circuit controlling armature shown is in the shape of a spring finger 16 which has one end fastened to the arm 8 of the driving lever. This spring finger armature extends loosely through the slot 9 in the bent end of the arm 8 so that while the secondary armature is carried by the driving-lever there is a little lost motion between these parts owing to the slot. The secondary armature 16 carries a contact 17 which is designed to engage a fixed contact 18 at the end of a yielding arm 19 that is fastened to the insulated piece 20 at the end of the magnet, and to which arm one end of the magnet winding is connected. The free end of the secondary armature is adapted to be attracted by the extension 3 of the magnet core. Fastened to the pole extension 3 is a spring finger 21 which has its free end bent outward and provided with a hump 22, which outwardly inclined end and hump extend into the path of the free end of the secondary armature.

15 When the contacts of the secondary armature and arm 19 are engaged the magnet is energized so as to attract the main armature arm 7, retract the pawl over the ratchet wheel and tension the driving spring. During the first part of this movement of the main armature the magnetic pull of the core extension and the hump 22 of the spring finger hold the 20 secondary armature with the circuit contacts engaged until the lost motion between the secondary and the main armature is taken up, and the pull of the magnet on the main armature is increased sufficiently to cause the secondary armature to snap past the hump on the spring finger and thus open the circuit quickly. As the ratchet wheel rotates under the pull of the driving spring and the main armature recedes from the magnet the 25 end of the secondary armature drags down the inclined end of the spring finger 21 until the contacts are nearly closed, and then when the end of the secondary armature reaches the hump in the spring finger it is under a slight tension, and owing to this tension it snaps past the hump and lightly engages the contact 17 with the fixed contact 18, which causes the core of the magnet to be slightly magnetized. The slight magnetism thus developed 30 in the core will act through the pole-piece 3 to attract the free end of the secondary armature 16 and hence pull the contacts 17 and 18 into tighter engagement with the effect of correspondingly increasing the energy of the 35 magnet until it is sufficient to pull the main-

armature arm 7 of the lever 6 inward against the counterurge of the driving-spring 14. This action of these parts is repeated each time the circuit is closed and opened through the secondary armature.

70 One end of the magnet winding may be connected with the energizing circuit terminal at 23 and the other end of the magnet winding, as stated, is connected with the contact arm 19, while the other circuit terminal may be grounded on the plate at any suitable point as at 24.

75 The ratchet wheel, that is rotated by the pawl and driving spring, has two forwardly extending pins 25 that are designed to, when the wheel is rotated by the push of the pawl, engage yielding fingers 26 that are attached to a disk 27 which is fastened to the arbor 28 of the time train, that may be any common and well known type. When driving pressure is exerted on the time train these fingers close together and provide a positive driving connection, but the fingers have sufficient resilience to bear against the pins, and keep in close engagement with the pins on the 80 ratchet wheel at all times so as to ensure constant driving pressure on the time train.

85 The invention claimed is:

1. In an operating-mechanism for electric 90 clocks, the combination with an electro-magnet having two complementary pole-pieces; of a circuit therefor; a two-armed pivotal operating-lever having one arm carrying a main armature positioned for attraction by one of the said pole-pieces and the other arm carrying a secondary armature mounted thereon with capacity for limited relative movement and positioned for attraction by the other of the said pole-pieces; a contact-member interposed in the said circuit and operably connected to the said secondary armature; a second contact-member also interposed in the said circuit and positioned to be engaged by the first-mentioned contact-member; and a driving-spring connected to the 95 said lever and normally urging the primary armature away from its complementary pole-piece and the said secondary armature toward its complementary pole-piece.

100 2. In an operating-mechanism for electric 100 clocks, the combination with an electro-magnet having two complementary pole-pieces; of a circuit therefor; an L-shaped pivotal operating-lever having two arms extending away from its pivot-point at substantial 110 right angles; a main armature carried by one of the said arms and positioned for attraction by one of the said pole-pieces; a secondary armature mounted upon the other of the said arms with capacity for limited relative 115 movement with respect thereto and positioned for attraction by the other of the said pole-pieces; a contact-member interposed in the said circuit and operably connected to the 120 said secondary armature; a second contact- 125 member interposed in the said circuit and operably connected to the said secondary armature; a second contact- 130

member also interposed in the said circuit and positioned to be engaged by the first-mentioned contact-member; and a driving-spring connected to the said lever and normally urging the primary armature away from its complementary pole-piece and the said secondary armature toward its complementary pole-piece.

3. In an electric clock, the combination with an electro-magnet having two complementary pole-pieces; of a circuit therefor; a primary armature and a secondary armature connected together with capacity for limited relative movement and respectively positioned for attraction by one of the said complementary pole-pieces; a contact-member interposed in the said circuit and operably connected to the said secondary armature; a second contact-member also interposed in the said circuit and positioned to be engaged by the first-mentioned contact-member; a driving-spring connected to the said primary armature and normally urging the same away from its complementary pole-piece and the said secondary armature toward its complementary pole-piece.

4. In an electric clock, the combination with an electro-magnet having an L-shaped core terminating in two complementary pole-pieces; a circuit therefor; a primary armature and a secondary armature connected together with capacity for limited relative movement and respectively positioned for attraction by one of the said complementary pole-pieces; a contact-member interposed in the said circuit and operably connected to the said secondary armature; a second contact-member also interposed in the said circuit and positioned to be engaged by the first-mentioned contact-member; and a driving-spring connected to the said primary armature and normally urging the same away from its complementary pole-piece and the said secondary armature toward its complementary pole-piece.

5. In an electric clock, the combination with an electro-magnet having an L-shaped core terminating in two complementary pole-pieces; a circuit therefor; a primary armature and a secondary armature arranged at a substantial right angle with respect to each other and connected together with capacity for limited relative movement and respectively positioned for attraction by one of the said complementary pole-pieces; a contact-member interposed in the said circuit and operably connected to the said secondary armature; a second contact-member also interposed in the said circuit and positioned to be engaged by the first-mentioned contact-member; and a driving-spring connected to the said primary armature and normally urging the same away from its complementary pole-piece and the said secondary armature toward its complementary pole-piece.

6. In an electric clock, the combination with an electro-magnet having two complementary pole-pieces; of a circuit therefor; a primary armature and a secondary armature connected together with capacity for limited relative movement and respectively positioned for attraction by one of the said complementary pole-pieces; a contact-member interposed in the said circuit and operably connected to the said secondary armature; a second contact-member also interposed in the said circuit and positioned to be engaged by the first-mentioned contact-member; a detent engaging the said secondary armature and acting to yieldingly retard its movement toward its complementary pole-piece; and a driving-spring connected to the said primary armature and normally urging the same away from its complementary pole-piece and the said secondary armature toward its complementary pole-piece.

7. In an electric clock, the combination with an electro-magnet having two complementary pole-pieces; of a circuit therefor; a primary armature positioned for attraction by one of the said pole-pieces; a resilient secondary armature connected with the said primary armature for actuation thereby with capacity for limited relative movement with respect thereto and composed of a strip of spring material extended into line with the other of the said pole-pieces; a contact-member interposed in the said circuit and carried by the said resilient secondary armature; a second contact-member also interposed in said circuit and positioned to be engaged by the first-mentioned contact-member; and a driving-spring connected to the said primary armature and normally urging the same away from its complementary pole-piece and the said secondary armature toward its complementary pole-piece.

8. In an electric clock, the combination with an electro-magnet having an L-shaped core terminating in two complementary pole-pieces; of a circuit therefor; a primary armature positioned for attraction by one of the said pole-pieces; a resilient secondary armature composed of a strip of spring material and secured to the said primary armature and projecting therefrom at a substantial right angle and positioned for attraction by the other of the said pole-pieces; a contact-member interposed in the said circuit and carried by the said secondary armature; a second contact-member also interposed in the said circuit and positioned to be engaged by the first-mentioned contact-member; and a driving-spring connected to the said primary armature and normally urging the same away from its complementary pole-piece and the said secondary armature toward its complementary pole-piece.
